[57] ABSTRACT

In a logic circuit having a load MISFET of the depletion type, a MISFET logic circuit employs a logic block of a predetermined logic expression, and a MISFET of the enhancement type. The depletion type MISFET, the logic block and the enhancement type MISFET are connected in series. The enhancement type MISFET is driven by clock pulses so that, only when it is conductive, current flows through the series circuit. Thus, the amount of power consumption is lowered.

**MISFET (METAL-
INSULATOR-SEMICONDUCTOR FIELD-EFFECT
TRANSISTOR) LOGICAL CIRCUIT HAVING
DEPLETION TYPE LOAD TRANSISTOR**

BACKGROUND OF THE INVENTION

1. Field of the Invention

The present invention relates to a logic circuit composed of insulated gate field-effect transistors (hereinbelow termed "MISFETs"). More particularly, it relates to a MISFET logic circuit having a depletion type load transistor.

2. Description of the Prior Art

As the general logic circuit employing MISFETs, the so-called EE(enhancement-enhancement) system is known in which both MISFETs for a load and for drive are of the enhancement type. As means to reduce the power consumption of the above system, there is the clock drive system in which the load transistor is driven by clock pulses.

On the other hand, with the so-called ED (enhancement-depletion) system employing a depletion type MISFET as a load transistor, it is difficult to adopt the clock drive system similar to that of the EE system. Nevertheless, excellent properties such as low power consumption, high speed and high degree of integration are available due to the possibility of a low supply voltage and the constant current characteristic of the depletion type MISFET.

FIG. 5 shows the fundamental circuit of a logic circuit according to the ED system.

To be noted in regard to the fundamental circuit in the figure is the fact that, whenever drive transistor Q_d is conductive, current flows through a series circuit consisting of the drive transistor Q_d and load transistor Q_1 .

SUMMARY OF THE INVENTION

It is, accordingly, an object of the present invention to reduce the average quantity of current which flows through the series circuit, to thereby further lower the power consumption of a logic circuit according to the ED system.

Another object of the present invention is to provide a MISFET logic circuit having a depletion type load transistor, which circuit can be brought into a low power consumption without significantly increasing the number of transistors.

The present invention itself and the other objects of the present invention will become apparent from the following detailed description when taken with reference to the accompanying drawings.

BRIEF DESCRIPTION OF THE DRAWINGS

FIGS. 1 to 3 are connection diagrams of MISFET logic circuits employing depletion type load transistors arranged in accordance with the present invention;

FIG. 4 is a time chart for explaining the operation of the shift register in FIG. 3; and

FIG. 5 is a prior-art MISFET logic circuit employing a depletion type load transistor, which circuit has already been referred to.

**PREFERRED EMBODIMENTS OF THE
INVENTION**

FIG. 1 shows a MISFET logic circuit according to the present invention.

In the figure, Q_{11} designates a MISFET of the depletion type by which, even when no bias voltage is applied between the gate and the source, current flows between the source and the drain. The depletion type MISFET Q_{11} is used as a load transistor. On the other hand, $Q_{d1} - Q_{d3}$ indicate MISFETs of the enhancement type by which, when a prescribed bias voltage is applied between the gate and the source, current will begin to flow between the source and the drain. The enhancement type MISFETs are used as drive transistors.

In order to provide a good constant current characteristic, the gate electrode of the MISFET Q_{11} is connected to the source electrode thereof, namely, the output terminal of the logic circuit.

15 The MISFETs $Q_{d1} - Q_{d3}$ constitute a logic block LB which satisfies the logic expression $V_{out} = (V_A + V_B) \cdot V_C$ (when the conductivity type of the channel of each MISFET is P-type and when positive logic is adopted).

A MISFET Q_{d4} is further provided by the present invention. It has clock pulses ϕ applied to the gate electrode and is, thus, clock-driven. The pulse width of the clock pulse ϕ is made smaller than the pulse width of each of the input signals $V_A - V_C$.

The MISFETs Q_{11} and Q_{d4} and the logic block LB are 25 connected in series. The output signal V_{out} is derived from the connection between the logic block LB and the load MISFET Q_{11} . According to the present invention, however, it is also possible to connect the transistor Q_{d4} between the load MISFET Q_{11} and the logic 30 block LB, and to derive the output signal from the drain electrode of the transistor Q_{d4} .

With the MISFET logic circuit thus constructed, only when the MISFET Q_{d4} is rendered conductive by the 35 clock pulse ϕ , will current flow through the closed series circuit consisting of the MISFETs Q_{11} and Q_{d4} and the logic block LB. It is, therefore, possible to reduce the power consumption. The value of the output signal V_{out} is determined by the values of the input signals $V_A - V_C$ during the conduction period of MISFET Q_{d4} .

That is, the relation $V_{out} = (V_A + V_B) \cdot V_C$ holds during the conduction period.

With the MISFET logic circuit according to the present invention, the number of transistors which are serially connected between the output terminal and a ground terminal is increased by one in comparison with the number of the same in a circuit of the EE system. However, the area occupied by the elements does not become larger, but it becomes smaller under some conditions.

50 The reason is that, with the EE system, the number of transistors to be connected in series from the output terminal is limited to at most two, whereas with the ED system, about four transistors can be connected in series from the output terminal under the condition of 55 obtaining the same output level at the same operating speed.

A quantitative explanation of the reason will be omitted for brevity. In short, it is with the ED system that the connection of the current limiting MISFET in series 60 with the logic block LB can be readily accomplished.

FIG. 2 shows another embodiment according to the present invention, which is an AND - OR circuit often required in a digital control circuit, etc.

In the figure, $Q_{d5} - Q_{d10}$ indicate enhancement type 65 MISFETs. With a respective pair of the transistors forming each set, logic blocks $LB_1 - LB_3$ are constructed. Depletion type load MISFETs $Q_{12} - Q_{14}$ are connected to the respective logic blocks. Each of the

logic blocks LB₁ – LB₃ is so arranged as to have the function of a two-input NAND circuit. Output signals derived from the logic blocks LB₁ and LB₂ are utilized as input signals of the logic block LB₃. It will be understood that output signal V_{out} is, accordingly, represented by the logic expression:

$$V_{out} = (V_D \cdot V_E) \cdot (V_F \cdot V_G) = V_D \cdot V_E + V_F \cdot V_G.$$

The feature of the AND – OR circuit lies in that a single MISFET Q_{d11} is connected commonly in series to the respective logic blocks, whereby the current flowing through the three logic blocks is limited by the single transistor Q_{d11}. Even with such an arrangement, the actual logic is similarly determined during the period of the width of the clock pulse ϕ applied to the transistor Q_{d11}.

In this manner, according to this embodiment, a single MISFET may be provided for an aggregate of logic blocks. The embodiment therefore attains the object of reducing the power consumption, and is advantageous in being capable of increasing the degree of integration. The single MISFET must usually absorb the total amount of current flowing through the logic blocks belonging to the aggregate to which the MISFET is connected. In consequence, it must be a MISFET larger (lower in resistance) than the transistors constituting the logic blocks. Of course, in addition to the form of the single MISFET, the current limiting MISFET may take the form of a plurality of MISFETs connected in parallel. Since the logic is not dynamic, using a four-phase clock, the embodiment also has the feature that the current limiting MISFET may be arranged at a place convenient for layout.

FIG. 3 shows still another embodiment of the present invention, which is a two-phase dynamic shift register of two bits.

In the figure, enhancement type MISFETs Q_{d12} – Q_{d15} are connected to depletion type load MISFETs Q₁₅ – Q₁₈, respectively. An enhancement type MISFET for current limitation Q_{d16} is connected commonly in series to the MISFETs Q_{d12} and Q_{d14}, and its gate electrode is applied with clock pulses ϕ_1 as shown in FIG. 4. A MISFET Q_{d17} is connected commonly in series to the MISFETs Q_{d13} and Q_{d15}, and its gate electrode is applied with clock pulses ϕ_2 (FIG. 4) which differ in phase from the clock pulses ϕ_1 .

The MISFETs Q₁₅, Q_{d12} and Q_{d16} constitute an inverter circuit. Similarly, the other MISFETs (including Q_{d16}) constitute three inverter circuits. The respective inverter circuits are connected in cascade through enhancement type MISFETs for transfer Q_{t1} – Q_{t3}. From the inverter circuit at the final stage, an output signal is derived through a MISFET Q_{t4}. The gate electrodes of the MISFETs Q_{t1} and Q_{t2} are applied with the clock pulses ϕ_1 , while the gate electrodes of the MISFETs Q_{t2} and Q_{t4} are applied with the clock pulses ϕ_2 . The gate electrode of the MISFET Q_{d12} is applied with an input signal V_{in} (FIG. 4) which is synchronized with the clock pulses ϕ_2 .

The operation of the shift register thus constructed will now be described with reference to the time chart in FIG. 4. In the figure, the upper level indicates a logical "1" (ground potential), and the lower level a logical "0" (a negative potential).

When the clock pulse ϕ_1 becomes 0 to render the MISFET Q_{d16} conductive, an output signal of the first inverter circuit or the source potential V₁ of the MISFET Q₁₅ becomes the inverted signal $\bar{V}_{in}$ of the input signal V_{in}. Since the transfer MISFET Q_{t1} is also con-

ductive at this time, the output signal V₁ is fed through the MISFET Q_{t1} to the MISFET Q_{d13}, and is stored by the gate capacitance of the MISFET Q_{d13}. Similarly, when the clock pulse ϕ_2 becomes 0 to render the MISFETs Q_{d17} and Q_{t2} conductive, the inverted signal of the signal stored in the MISFET Q_{d13} is written into the gate capacitance of the MISFET Q_{d14}. Accordingly, the gate potential V₂ of the MISFET Q_{d13} becomes equal to a signal with the inverted signal of the input signal V_{in} delayed by the phase difference between the clock pulses ϕ_1 and ϕ_2 , as the gate potential V₂ is synchronized with the clock pulse ϕ_1 , and the input signal V_{in} is synchronized with the clock pulse ϕ_2 . Since the periods of the clock pulses ϕ_1 and ϕ_2 are equal, the gate potential V₄ of the MISFET Q_{d14} ultimately becomes equal to a signal with the input signal V_{in} delayed by one period (one bit) of the clock pulses ϕ_1 or ϕ_2 . This is also apparent from the time chart in FIG. 4.

As illustrated in FIG. 4, the output potential V₁ of the first inverter is forced to the value 0 irrespective of the input signal when the clock pulse ϕ_1 is held at 1. Only when the clock pulse ϕ_1 falls to 0, is the output potential V₁ transferred through the MISFET Q_{t1} to the MISFET Q_{d13} and written thereinto. The gate potential V₂ therefore sustains only the correct value of the output potential V₁ until the clock pulse ϕ_1 subsequently changes to 1. For a similar reason, the period during which the output potential V₁ exhibits the correct value becomes equal to the pulse width of the clock pulse ϕ_1 , and is shorter than such period of the input signal V_{in}. However, this causes no problem since the period during which the gate potential V₂ exhibits the correct value becomes equal to the period of the clock pulses ϕ_1 .

In this manner, the period during which the output signal derived from each logic block indicates the correct value is made short with respect to the pulse width of the clock pulse. When it must be corrected, the logic circuit in FIG. 1, for example, may be operated such that the signal is fed from the logic block LB to the next stage of the circuit through the transfer MISFET which is triggered by the clock pulse ϕ .

The shift register described above has the following advantages, which will be easily understood from the explanation of the embodiments in FIGS. 1 and 2:

1. The power consumption is lowered; and
2. The number of transistors for lowering the power consumption can be made smaller than the number of logic blocks.

What I claim is:

1. A MISFET logic circuit comprising:
a first terminal to which a source of D.C. potential is supplied;
a second terminal serving as a common terminal;
a third terminal to which ground potential is applied;
a plurality of depletion type MISFETs each having a drain electrode connected to said first terminal, and a source electrode and a gate electrode connected together;
- a plurality of logic blocks, each having a reference terminal, an output terminal, and at least one input terminal, the output terminals being connected to the respective source electrodes of said depletion type MISFETs and the reference terminals being connected to said second terminal, each of said logic blocks comprising at least one first enhancement type MISFET having a drain electrode connected to the output terminal thereof, a gate elec-

trode connected to a respective input terminal, and a source electrode coupled to the reference terminal thereof; a second enhancement type MISFET having a resistance lower than said at least one first enhancement MISFET and having a drain electrode connected to said second terminal, a source electrode connected to said third terminal, and a gate electrode; means for supplying a clock pulse signal to the gate electrode of said second enhancement type MISFET; and means for supplying input signals to said input terminals, thereby causing the logic functions to be effected by said logic blocks only during the period of the width of the clock pulse.

2. A MISFET logic circuit comprising:

first and second depletion type MISFETs, each having a drain electrode, a source electrode, and a gate electrode connected to the source electrode; a first terminal serving as a common terminal; a second terminal to which ground potential is applied; a first logic block having a reference terminal, an output terminal and at least one input terminal, said output terminal being connected to the source electrode of said first depletion type MISFET and said reference terminal being connected to said common terminal, said first logic block including at least one first enhancement type MISFET having a drain electrode electrically connected to said output terminal, a source electrode coupled to said reference terminal and a gate electrode connected to a respective input terminal; a second logic block having a reference terminal, an output terminal and at least one input terminal, the output terminal being connected to the source electrode of said second depletion type MISFET and the reference terminal being connected to said common terminal, said second logic block including at least one second enhancement type MISFET having a drain electrode connected to the output terminal, a gate electrode connected to a respective input terminal, and a source electrode coupled to the reference terminal; a third enhancement type MISFET having a resistance lower than the first and second enhancement type MISFETs and having a drain electrode con-

nected to said common terminal, thereby commonly connecting the reference terminals of said first and second logic blocks, a source electrode connected to said second terminal, and a gate electrode;

means for supplying an electrical potential to the drain electrodes of said first and second depletion type MISFETs;

means for supplying a clock pulse signal to the gate electrode of said third enhancement type MISFET; means for supplying an input signal to the input terminal to which the gate electrode of one of said at least one first enhancement type MISFET of said first logic block is connected; and

wherein the output terminal of said first logic block is connected to the gate electrode of one of said at least one second enhancement type MISFET of said second logic block.

3. A MISFET logic circuit comprising:

a depletion type MISFET having a drain electrode, a source electrode and a gate electrode connected to said source electrode;

a common terminal;

a logic block connected between the source electrode of said depletion type MISFET and said common terminal, said logic block being constructed by a plurality of signal paths each having at least one first enhancement type MISFET having a drain electrode electrically connected to the source electrode of said depletion type MISFET, a source electrode and a gate electrode, all of the signal paths being terminated at said common terminal; a second enhancement type MISFET having a resistance lower than said at least one first enhancement type MISFET when conducting and having a drain electrode connected to said common terminal, a source electrode connected to said ground terminal, and a gate electrode;

means for supplying an electrical potential to the drain electrode of said depletion type MISFET;

means for supplying a clock pulse signal to the gate electrode of said second MISFET; and

means for supplying input signals to the gate electrodes of said first enhancement type MISFETs in said logic block.
